INVENTOR.
Frank A. Magee.

BY *Albert G. Bell*
ATTORNEY.

UNITED STATES PATENT OFFICE

FRANK A. MAGEE, OF CHICAGO, ILLINOIS

PORTABLE RADIO RECEIVING SET

Application filed November 30, 1926. Serial No. 151,773.

5 My invention relates to an improved construction of radio receiving set by which the entire apparatus involved in receiving and amplifying the radio impulses, as well as the batteries required, a loud speaker and a receiving loop, are all contained in a single cabinet or case of such size and total weight that it may readily be carried to any desired location and used wherever desired to reproduce radio programs without the necessity of adding anything to the set or attaching any outside wires of any kind to it.

10 It will be understood that in connection with receiving sets of the kind referred to, intended to be portable, it is of the utmost importance that the cabinet or case be of as small size and weight as possible, and at the same time it is necessary that the radio receiving set be of the multi-stage variety and 15 constructed to amplify the received impulses effectively and without distortion. I find it desirable to employ five stages in the receiving set, two of them being radio frequency stages followed by a detector stage and this 20 in turn followed by two stages of audio frequency. My invention pertains particularly to accomplishing the results set forth by several features of construction and a particular arrangement of the parts resulting in a 25 much reduced bulk of the outfit as a whole and a relatively small weight of the apparatus in its complete condition. These several features of improvement characterizing my invention will best be understood by reference to the accompanying drawings showing a preferred embodiment thereof in which 30

Fig. 1 shows my receiving set in back elevation in open condition.

35 Fig. 2 is a sectional view of the parts shown in Fig. 1 taken along the line 2—2, with the covers in their closed positions,

40 Fig. 3 shows in a view similar to Fig. 2 the front cover removed and the receiving set drawn from the case for inspection or repair,

45 Fig. 4 is a front elevation of my receiving

set with the front cover broken away to show a partial outside elevation and a partial elevation of the panel board and front inner wall of the case,

50 Fig. 5 is a detail view to an enlarged scale showing the battery switch in front elevation and a part of the front cover in place and broken away,

55 Fig. 6 is a vertical sectional view to an enlarged scale of the parts of the construction shown in Fig. 5, this view being taken along the line 6—6 in Fig. 4 and

60 Fig. 7 shows in front elevation to a reduced scale, the front cover removed and in the relation it occupies to the case when the set is in use.

65 Similar numerals refer to similar parts throughout the several views.

70 As shown in Figs. 1 and 2 my construction consists of a case 10 having a loud speaker 11 mounted again the top wall thereof and occupying a part of the upper portion of the case, the speaker being connected with a receiver unit 12. Below the speaker 11, several cells 13 of dry battery are disposed on their sides extending from back to front of the case, in which position they are supported by a horizontal partition 14 extending the full width of the case. The batteries 13 occupy but part of the space immediately above the partition 14 and in the remaining space, left by the batteries 13 and the speaker 11, two blocks of dry batteries 15 are supported by the partition 14, one upon the other, the size of the batteries 15 being such that they 75 substantially fill said remaining space. The batteries 13 are of the class commonly known as "A" batteries for the purpose of heating the filaments of the vacuum tubes and the batteries 15 are of the class commonly called "B" batteries for applying to the plates of the vacuum tubes the requisite voltages.

80 The receiving set consists of a control panel 16 and a sub-panel 17 secured together in any convenient manner so that the sub-panel 85

50

55

60

65

70

75

80

85

90

17 is in horizontal position and slightly above the lower edge of the panel 16. The vacuum tubes 18 are mounted on the back edge of the sub-panel 17 and the apparatus employed in the receiving set is mounted on the panel 16 and the sub-panel 17 in any convenient manner to secure the contemplated results in view of the particular hook-up used. The main wiring of the set is preferably in the space between the sub-panel 17 and the bottom of the case 10. Near the rear edge of the sub-panel 17 bolts or screws 19 are secured to the bottom wall of the case and project upwardly therefrom through the sub-panel 17 to hold it in place in the case, nuts 20 being employed to hold the sub-panel in spaced relation from the bottom of the case to clear the wiring on the sub-panel. The sub-panel 17 is preferably held in place on the bolts 19 by the thumb nuts 21 as indicated. As a result of the construction just described, when it is desired to examine the apparatus carried by the panel 16 and the sub-panel 17, all that is necessary is to first remove the vacuum tubes 25 from their sockets, and then to remove the thumb nuts 21, after which the sub-panel 17 may readily be lifted at its rear edge from engagement with the bolts 19, and the panel 16 and the sub-panel 17 may be moved bodily 30 from the case as indicated in Fig. 3, this being permitted by the cable of conductors 22 connecting the apparatus with the batteries and loud speaker.

The relation between the loud speaker, the batteries and the apparatus of the receiving set above described is important, as it effects a maximum separation between the receiver unit 12 and the apparatus involved in the radio frequency stages, eliminating the communication of microphonic noises from the unit 12 to the amplifying apparatus.

It will be understood that any desired hook-up may be used in connection with the receiving set and that no claim is made for any particular hook-up or arrangement of apparatus on the panel 16 and sub-panel 17 in the present application, for which reason the apparatus and its connections are not specifically described herein.

50 It will be noted that the partition 14 does not extend to the rear surface of the case 10, but is cut away over the vacuum tubes 18. This construction is employed to afford a clearance over the vacuum tubes so that they 55 may be removed from their supporting sockets and inserted therein, at the same time maintaining the distance between the bottom of the batteries and the bottom wall of the case at a minimum. Were the shelf 14 extended to the rear edge of the case, the latter would necessarily be higher and more bulky, thus defeating in this regard, the desired condition of extreme compactness.

The back of the case 10 has hinged thereto a cover 23 which is held in closed position by

suitable fastening devices, preferably snap catches, so that ready access may be had to the batteries and vacuum tubes for replacement purposes without disturbing any of the other parts of the apparatus and without requiring the removal of the receiving set from the case. 70

The case 10 is provided with an inner front wall 24 substantially in the plane of the panel 16, and in the upper part of this front wall 75 an opening 25 is formed immediately under the top wall of the case 10, this opening being in line with the delivery opening of the speaker 11 to permit the passage of sound waves from the speaker to the hearer. To enclose the front of the case and the control knobs carried by the panel 16, I provide a false front cover 26 extending from substantially the plane of the outer surface of the panel and front wall 24 of the case, and this front cover 80 is provided with edge flanges 26a, forming a recess in the cover of a sufficient depth to clear the control knobs on the panel 16. In the said recess I secure blocks 27 in the corners thereof, to support the turns of wire 28 85 constituting the receiving loop of the set, the corner blocks being so placed that the loop wires lie along the inner surfaces of the flange pieces 26a of the front cover. In this manner I am able to give the loop wires an effective 90 and efficient arrangement and relation, at the same time entirely protecting them from accidental injury. As indicated in Fig. 4, the front cover 26 is hinged preferably at its lower edge as indicated at 29, to the case 10, the 100 hinges employed being preferably of the separable kind so that when the cover is swung to its open position, it may be removed from the case to permit its use as a receiving loop. Fastening devices of any convenient kind, for example spring catches as indicated at 38, 105 may be employed to hold the front cover 26 in its closed condition.

To protect the batteries 13 from being connected and subject to current drain when the case is closed, I locate a battery switch 30 in one of the lower corners of the panel 16 and preferably employ a switch of the rotary kind, having a short operating arm 30a. The switch 30 is purposely so located on the panel 16, relatively to the adjacent corner block 27 in the front cover 26, that when the switch is in its closed or "on" position, the arm 30a extends into the path of the said corner block, the proportion of the parts being such that for this position of the switch, the front cover 110 cannot be closed on account of the corner block 27 last referred to, striking the arm 30a. With the switch 30 in its open or "off" position however, the arm 30a is in line with the clearance space between the adjacent corner block 27 and the adjacent corner of the front cover, 115 so that the said corner block is then free to move to the position it occupies when the front cover is closed and in this way a safe- 120

guard is provided insuring that the switch 30 shall be turned to its "off" position when the set is not in use and the front cover is closed.

As shown in Fig. 7, I preferably provide the inside of the front cover 26 with a spring clip 31 to hold the connecting wires 28a of the loop, when the set is not in use, these connecting wires being preferably connected at their ends with small plugs 32. I also preferably 10 secure to the inside of the front cover 26, a second spring clip 33 for holding within the cover a supporting post 34 having split ends as indicated to support the loop when in use. One of the end flange members 26a is provided with a socket 35 and the top of the case 10 is provided with a similar socket 36 to receive the ends of the post 34 to hold the loop in vertical position and at the same time permit free turning of it during the use of the set. The 15 panel 16 is preferably provided with jacks 37 to receive the plugs 32 during the use of the set.

The case 10 is provided with a handle 39 to facilitate carrying the set when desired.

As a result of my construction I am able 25 to produce a complete portable radio receiving set including batteries, loud speaker and loop aerial in a case measuring over all when closed only eight and one half inches from front to rear, ten inches in height and twelve and one half inches in length and I am able to 30 reduce the weight of the entire outfit to twenty four pounds. This result is secured using standard "A" batteries of the cylindrical kind 35 measuring two and one half inches diameter and six and one half inches long each, and two standard 45 volt "B" battery blocks each measuring two and a half inches by four and a quarter inches by six inches. The vacuum tubes employed are preferably of the kind 40 known as four volt tubes using a very small filament current. These figures are mentioned specifically on account of important 45 requisites of a portable radio receiving set being compactness and lightness. At the same time I am able to use as a part of the 50 equipment a five tube receiving set and a speaker construction capable of delivering results comparing favorably with many stationary five tube receiving sets.

While I have shown my invention in the particular embodiments above described, it will be understood that I do not limit myself to this exact construction as I may employ 55 equivalents known to the art at the time of the filing of this application without departing from the scope of the appended claims.

What I claim is:

1. In a portable self contained radio receiving set, the combination of a casing, radio receiving and amplifying apparatus including a plurality of vacuum tubes in the bottom part of said casing, a loud speaker and receiver unit in the top part of said casing, a 60 shelf fixed in said casing, and batteries car-

red by said shelf between said receiver unit and said receiving and amplifying apparatus to effect a maximum separation of the former from the latter to eliminate microphonic noise. 70

2. In a portable self contained radio receiving set, the combination of a casing, a radio receiving and amplifying apparatus including a plurality of vacuum tubes in said casing, a vertical control panel across the front of said casing, a switch having a movable arm, a recessed cover for enclosing said panel, a block in the recess of said cover in line with said switch arm for the "on" position of said arm to prevent closing said cover for said "on" position and clearing said arm and switch for the "off" position of said arm, and a loop aerial in said cover recess and supported in part by said block. 75 80

3. A portable radio receiving set comprising a casing, a handle for said casing, a movable closure for the rear of said casing through which the apparatus within said casing is rendered accessible, a removable false front cover for the front of said casing, and means on said cover and the top of said casing whereby said cover is mountable for rotational movement on the top of said casing. 85 90

4. A portable radio receiving set comprising a casing having an inner front wall, a handle for said casing, a movable closure for the rear of said casing through which the apparatus within said casing is rendered accessible, a removable false front cover for the front of said casing having a loop antenna therein, and means whereby said cover is mountable for rotational movement on the top of said casing thereby to form an antenna frame adjustable to any horizontal direction without disturbing the casing. 95 100 105

5. A portable radio receiving set comprising a casing having an inner front wall, a handle for said casing, a movable closure for the rear of said casing through which the apparatus within said casing is rendered accessible, an apparatus carrier insertable into said casing from the front and having a front panel forming part of the front wall of said casing, a removable false front cover for the front of said casing, and means whereby said cover is mountable for rotational movement on said casing, said inner front wall having an opening therein above said front panel adapted to constitute the outlet for the sound waves issuing from within. 110 115 120

6. A portable container for radio receiving apparatus comprising a five sided casing, a movable closure for the rear of said casing, a false front cover for the front of said casing and means whereby said false front cover may be rotatably mounted on said casing at a point spaced from the front thereof where free rotation of said cover is unobstructed by the casing, said false front cover having means for supporting a loop antenna therein. 125 130

7. A portable container for radio receiving apparatus comprising a five sided casing, a movable closure for the sixth side of said casing, a false cover for one of said six sides, said false cover having means for supporting a loop antenna therein, and means whereby said loop antenna may be rotatably mounted on said casing at the top thereof and spaced therefrom.

10 In witness whereof, I hereunto subscribe my name this 26th day of November, A. D. 1926.

FRANK A. MAGEE.
